(57) **CLAIM**

The ornamental design for a carrier quadricycle, as shown and described.

DESCRIPTION

FIG. 1 is a front right side isometric view of the carrier quadricycle in accordance with the present invention;
FIG. 2 is a right side elevational view of the carrier quadricycle of FIG. 1;
FIG. 3 is a front perspective view of the carrier quadricycle of FIG. 1;
FIG. 4 is a rear perspective view of the carrier quadricycle of FIG. 1;
FIG. 5 is a left side elevational view of the carrier quadricycle of FIG. 1;
FIG. 6 is a top view of the carrier quadricycle of FIG. 1;
FIG. 7 is a top view of the carrier quadricycle of FIG. 1, in the steering left configuration;
FIG. 8 is a top view of the carrier quadricycle of FIG. 1, in the steering right configuration; and,
FIG. 9 is a right side elevational view of the carrier quadricycle of the FIG. 1 with the platform in configuration for loading or unloading of a wheelchair and user as well as any commercial or industrial object.
